UNITED STATES PATENT OFFICE.

KARL PROBST, OF TOLEDO, OHIO.

ELECTRIC-VEHICLE CONTROL.

Application filed February 13, 1922. Serial No. 535,988.

To all whom it may concern:

Be it known that I, KARL PROBST, a citizen of the United States of America, residing at Toledo, in the county of Lucas and 5 State of Ohio, have invented certain new and useful Improvements in Electric-Vehicle Controls, of which the following is a specification, reference being had therein to the accompanying drawings.

10 The invention relates to electric vehicles of the type operated by storage batteries, and it is the object of the invention to obtain greater efficiency or economy in current consumption; a longer life of the batteries; 15 also, longer life of the vehicle parts due to smoother starting. In the present state of the art the common type of control used for regulating the speed and torque of the motor is a system where a single controller 20 in successive positions of adjustment both varies the motor connections and the battery connections alternatively in series or parallel, and the arrangement is such as to furnish a plurality of speeds by successive adjustments with the last adjustment furnishing the highest voltage and greatest current 25 consumption. If such a control is carefully manipulated, it is possible to obtain both efficiency and any desired speed without 30 injurious effect, but unfortunately the average driver will not exercise the care required for such result. Thus in starting the car, instead of slowly manipulating the controller to pass from one position to another, 35 the operator will frequently quickly adjust to the highest position, thereby drawing a volume of current which is wasteful of the energy and is detrimental to the electrical parts. If the controller is so designed 40 as to avoid this result, then there will not be sufficient current for the maximum demand. For instance, with an electrically driven delivery wagon, it may be necessary to provide for a maximum speed of 15 to 35 45 miles an hour for long distance traveling, whereas the average speed required for house to house delivery may be very much less. This average speed could be obtained from a parallel connection of the batteries 50 giving a low voltage, but for the higher speed a series connection giving a high voltage is necessary. If, therefore, the controller is so designed as to give in its highest position of adjustment the high voltage 55 required for the maximum speed, there is nothing to prevent the careless operator

from adjusting to this position in its house to house delivery, although no material advantage in speed is obtained.

It is the primary object of the present 60 invention to so design the control that the operator can not, without deliberately violating instructions, waste current in the normal operation of the machine or strain the electrical parts. At the same time provision 65 is made for obtaining the higher voltage and, secondly, greater speed where necessary. The desired results are obtained by dividing the control into separately operable units, one for normal operation and 70 the other for abnormal operation. More specifically, there is provided one control unit for varying the speed of the motor by changing motor or rheostat connections or both while the other unit provides for 75 change in voltage by shifting from parallel to series connection of the batteries. Thus in normal operation, where the vehicle is driven from house to house, there is no occasion for using the battery control, this 80 being adjusted to give a parallel arrangement of the batteries and low voltage. However, it is possible at any time where the vehicle is traveling long distances, to increase the speed by changing the battery 85 control to the series arrangement.

In the drawings:—

Figure 1 represents diagrammatically my improved system of control;

Figure 2 is a side elevation of the battery 90 controlling switch;

Figure 3 is an end elevation thereof.

A and B represent two equal sections of the storage battery. C is the motor, and D the controller for normal operation. 95 E is an auxiliary controller which is used only for maximum speed. The controller D may be of any suitable construction (not shown in detail) and may be connected to the motor so as to control the latter either 100 by variation in the connection to the internal windings or by use of an external rheostat, or both, these forming no part of my invention. The auxiliary controller E may also be of any suitable construction, 105 but as specifically shown in Figures 2 and 3, it consists in a pair of switch blades F and F' which are pivoted to the contacts G and G' and may be alternatively connected to the contacts H, H' or I, I'. The circuits, as 110 diagrammatically shown include a connection J from the positive pole of the battery

A to the contact H, a connection K from the negative pole of the battery B to the contact G', a connection L from the negative pole of the battery A to the controller 5 D, a connection M from the controller D to the contact G, a connection N from the negative pole of the battery A to the contact H', and a connection O from the positive pole of the battery B to the contact G. 10 There is also a cross-connection P between the contacts H and I', a connection Q from the negative pole of the battery A to a charger coupling, and a connection R from the positive pole of the charger coupling 15 to the contact I. As the design of the main controller D or the particular connections used between the same and the motor are not essential to the invention, these are not illustrated in detail. 20 With the arrangement of circuits as described, when the switch E is adjusted with the blades F and F', connecting respectively the contacts G, H, and G', H' as 25 shown in full lines in Figure 1, the batteries A and B are connected in parallel and in this position current at low voltage is supplied to the controller D and from the latter to the motor. When the switch E is 30 adjusted with the blades F and F', connecting respectively the contacts G, I, and G', I', as indicated in dotted lines in Figure 1, the batteries A and B are connected in series and furnish current at high voltage to the controller. Also, in this latter position 35 the charger coupling is connected so that the battery may be charged by engaging said coupling with a suitable source of charging current.

When the switch E is adjusted for low 40 voltage, the vehicle may be used for house to house delivery and there is seldom, if ever, any occasion for using the higher voltage for this purpose. Thus the greatest efficiency or economy of current is obtained; the life of the electric parts due 45 to low current handling is increased; and the mechanical parts of the vehicle have longer life due to smoother starting of the vehicle. On the other hand, when speed is important, the switch E may be shifted to high voltage.

What I claim as my invention is:—

1. In an electrically driven vehicle, the combination with a motor and a storage 55 battery comprising two equal sections, of a controller for varying the speed of the motor without change in battery voltage,

a charger connection for the battery, and a switch for alternatively coupling said battery sections in parallel and in series 60 and for effecting in the latter position a coupling with said charger.

2. In an electrically driven vehicle, the combination with a motor and a storage battery, of a controller for varying the speed of the motor without changing battery voltage, a charger connection for the battery, and separately operable means for controlling the voltage, said means also effecting a coupling with said charger in 70 one position of adjustment.

3. In an electrically driven vehicle, the combination with a motor and a storage battery, of a controller for varying the speed of the motor without changing battery voltage, a switch for changing the battery connections from parallel to series, and a charger connected to said switch to effect a coupling with said battery in only one position of adjustment. 80

4. In an electrically driven vehicle, the combination with a motor and a storage battery, of a controller for varying the speed of the motor without changing battery voltage, a switch for changing the battery connections from parallel to series, and a charger connected to said switch to effect a coupling with said battery only when the latter is in series arrangement. 85

5. In an electrically driven vehicle, the combination with a motor and a storage battery comprising a plurality of sections, of a controller for varying the speed of the motor without changing battery voltage, separately operable means for coupling said battery sections together in different arrangements to vary the effective voltage, and a charger arranged to be coupled with said battery in only one of said different arrangements of battery sections. 90 95

6. In an electrically driven vehicle, the combination with a motor and a storage battery comprising two equal sections, of a controller for starting said motor and varying the speed thereof, a separately operable switch for connecting said battery sections alternately in parallel and series, and a charger arranged to be coupled with said battery only when said sections are in series arrangement. 100 105

In testimony whereof I affix my signature.

KARL PROBST.
